(57) CLAIM

The ornamental design for a garden kneeler, as shown and described.

DESCRIPTION

FIG. 1 is a front, right and top perspective view of a garden kneeler, showing our design.

FIG. 2 is a rear, left and bottom perspective view thereof.

FIG. 3 is a front elevation view thereof.

FIG. 4 is a rear elevation view thereof.

FIG. 5 is a left side view thereof.

FIG. 6 is a right side view thereof.

FIG. 7 is a top plan view thereof.

FIG. 8 is a bottom plan view thereof; and,

FIG. 9 is an enlarged view of portion 9 shown in FIG. 1. The broken lines in the drawings depict portions of the garden kneeler that form no part of the claimed design. The long dash-short dash broken lines depict areas of enlargement and form no part of the claimed design.
